MACHINE FOR MAKING DOLL SHOES

John E. Eckstrom, Detroit, Mich.

Application May 1, 1953, Serial No. 352,390

10 Claims. (Cl. 12—12)

My invention relates to shoe machinery and more particularly to a machine for the making of miniature shoes such as doll shoes.

Doll shoes and the like are made up principally of a vamp, an inner sole and an outer sole, and these parts are generally glued together. They are generally made by hand, the operators becoming quite skilled in their manufacture. However, because of the seasonal nature of this business, it is quite customary with such manufacturers to break in quite a number of unskilled workers every year, and it takes several weeks for an operator to become skilled in the art of hand manufacture of these doll shoes. Many operators have proposed machines for the making of doll shoes, but no satisfactory machine has as yet been produced for the manufacture of these doll shoes. The general shoe making machinery while now completely mechanized, is not adaptable to the making of doll shoes, and of course a fully automatic machine is not desirable for several reasons.

It is an object of my present invention to avoid the many difficulties in the making of miniature shoes, such as doll shoes, by constructing a semi-automatic machine in which many of the complicated mechanisms of the modern shoe machinery art have been eliminated, but which will enable an operator to skillfully make doll shoes with a minimum of training and to produce such shoes in quantity faster than is possible with the hand methods employed today.

In machine made shoes of this type, it is difficult to stretch and smooth the vamp over the inner sole of the shoe to which it is to be secured without employing the complicated mechanisms which have been developed for the manufacture of shoes for humans. A further object of the present invention is to build a machine made doll shoe or the like by a semi-automatic machine having simplified parts and mechanisms, economical and easy to operate, but which serves to uniformly fold over and stretch the shoe vamp over the inner sole of the shoe without creasing or otherwise bunching up the folded over vamp portion.

For a more detailed understanding of my invention, reference may be had to the accompanying drawings illustrating a preferred embodiment of the invention, in which like characters refer to like parts throughout the several views, and in which

Fig. 1 is a vertical sectional view of the machine, showing the shoe last in a raised position with the vamp and inner sole assembled thereon.

Fig. 2 is a fragmentary plan view of the machine showing the side and end pressure plates in a retracted position and the shoe last lowered into position within the pressure plate assembly.

Fig. 3 is a side elevation view of the pressure plate assembly looking in the direction of the arrows on the line 3—3 of Fig. 2.

Fig. 4 is an end elevational view of the pressure plate assembly looking in the direction of the arrows on the line 4—4 of Fig. 2.

2

Fig. 5 is an exploded detail view of a shoe vamp and inner sole assembly on a last and showing how the outer sole is applied thereto.

Fig. 6 is a detail transverse sectional view through the completed shoe.

Fig. 7 is a diagrammatic view of the hydraulic system for actuating the machine.

Fig. 8 is a fragmentary plan view showing an intermediate part of the assembly and particularly illustrating how the toe and heel portions of the vamp are progressively folded over the inner sole and secured thereto.

Fig. 9 is a fragmentary plan view of the machine showing the sides of the vamp being folded over and secured to the inner sole of the shoe.

Fig. 10 is a similar fragmentary plan view of the machine showing the toe and heel portions of the vamp being folded over and secured to the inner sole of the shoe.

Figs. 11 and 12 are detailed sectional views taken respectively on the lines 11—11 and 12—12 of Fig. 9,

Fig. 13 is a sectional view taken on the line 13—13 of Fig. 10.

Fig. 14 is a plan view of the shoe last showing the adjustable heel section extended and the toe clamp in locked position on the shoe vamp.

Fig. 15 is a similar plan view of the shoe last showing the adjustable heel section retracted and toe clamp in released position preparatory to receiving the vamp of the shoe.

Fig. 16 is a vertical longitudinal sectional view taken on the line 16—16 of Fig. 14.

Fig. 17 is a vertical longitudinal sectional view taken on the line 17—17 of Fig. 15.

Fig. 18 is a vertical end view of the shoe last showing the vamp in position thereon in dotted lines.

Fig. 19 is a diagrammatic section through a master control valve, referred to hereafter as "Logan #6245 master control valve," and

Fig. 20 is a diagrammatic section through a bleeder valve, referred to hereafter as "Logan #6270 bleeder valve."

The preferred construction illustrated in the accompanying drawings comprises a last 10 mounted on a post or ram 11. A machine frame structure 12 supports all operable parts of the machine and the guides 14 are supported from the frame 12 by posts 15. A pair of side pressure plates 16 and toe and heel plates 17 and 18 respectively are supported by the guides 14. The guides 14 are provided with a central space 19, through which the last structure 10 is projected, this last structure 10 being mounted on the post or ram 11 which is selectively raised and lowered to respectively elevate the last structure 10 as shown in Fig. 1 and to then lower same into the recess or opening 19 into operable position wherein the upper face of the last structure is located parallel with and slightly below the under surface of the slides 16, 17 and 18, so that as the slides are advanced, they will press against the folded over vamp and sole.

While the last structure is disposed in an elevated position, the assembled vamp 20 of the doll shoe is mounted on the last structure, the marginal portion 20a of the vamp projecting slightly above the upper surface of the last structure 10. The inner sole 21 of the shoe is laid onto this upper surface of the last and the vamp is clamped to the last by means shown more in detail in Figs. 14 to 18 inclusive.

This clamping means comprises an eccentric or cam element 22 initially positioned as shown in Fig. 15. This cam element comprises an upper cam portion 22a and a lower cam portion 22b and is rotatably supported by spindle 22c. In Figs. 15 and 17 the cam portion 22a is in a retracted position and cam portion 22b is ad-

vanced to engage a pin 23 pushing same against the arm 24 of bell crank 25, the other arm 26 of the bell crank being forced away from engagement with the toe of the last structure 10. The vamp 20 is thus easily slipped into position onto this last structure 10 and when properly positioned, the cam element 22 is rotated 180 degrees by handle 22d into the position shown in Figs. 14 and 16, the cam portion 22a engaging the vamp and stretching same taut on said last structure, and the cam 22b is moved away from pin 23 allowing same to retract, and thereby permitting the bell crank actuated by spring 25A to move so as to bring the arm 26 into clamping engagement with the toe portion of the vamp to thereby additionally clamp the toe portion of the vamp to the last structure 10. The inner sole 21 is then laid onto the top face 27 of the last with the moistened glued face upward. The last structure 10 with the vamp 20 and inner sole 21 assembled thereon is now lowered into operative position as above set forth by means of an hydraulic actuating device 28, the frame 12 carrying a table or other suitable plate structure 29 serving to accurately locate the last structure 10 in operative position.

The upstanding marginal portion 20a of the vamp is now in readiness to be folded over and pressed onto the moistened glued face of the inner sole. The first step in this final assembly is to advance the side pressure plates 16, both side plates 16 being simultaneously advanced to fold over the side portions of the projecting vamp margin onto the inner sole (see Figs. 8, 9 and 11). Fig. 8 shows in accurate detail, this specific operation and it will be noted that the extreme forward corners of these side pressure plates 16 are slightly projected as at 16a and the under face is slightly beveled as at 16b (see Fig. 12). Thus the major portion of the vamp margin 20a at the side of the shoe is completely folded over and secured to the inner sole 21 of the shoe, but at the extreme end, as at 16c, the vamp is only partially secured to the sole. These side pressure plates are advanced and retracted by means of suitable hydraulically actuated devices 40.

Next, the side pressure plates 16 are retracted and the toe and heel pressure plates 17 and 18 are advanced (see Figs. 9, 10 and 13). The forward edge of both toe and heel pressure plates are concave in plan, the curvature being such as to provide for the corners or points 17a and 18a to first engage the shoe vamp (see Fig. 8). It will be noted that these points first engage the vamp at the point where same has been only partially folded over onto the inner sole, and as said toe and heel plates are advanced, the vamp margin is progressively folded over with a generally circular and radial motion serving to substantially smooth out any wrinkles that may have a tendency to form, and the last part of the vamp to be folded over and secured to the sole is that part at the center of the toe and heel. This action, in effect, is a wiping and stretching action and provides a finished product. The toe and heel plates are now retracted. The shoe last is now raised to the position shown in Fig. 1, and then the press member 50 is pressed down onto the assembly to secure the outer sole to the shoe and then retracted, thus completing the assembly. The cam element 22 carried by said shoe last is now actuated to release the completely assembled shoe from the last structure so that same can be manually removed in readiness for another operational cycle.

Fig. 7 illustrates one means for effectively carrying out the various sequences of operations described above, which comprises a conventional compressed air control equipment, and consists of two separate cycles.

In the first cycle, the cylinders A, B, C, D and E are controlled and activated by means of the right foot pedal assembly 60, the built-in bleeder valve of the foot pedal assembly, the bleeder valves Q, P, M, N and O, and the master control valves 65, 70 and 75. In the second cycle, the cylinder F is controlled and activated by

means of the left foot pedal 61, the built-in bleeder valve of the said foot pedal, and the master control valve 80. The normal position for the various air cylinders are as follows: the piston rod for cylinders B, C, D, 5 E and F are disposed in the innermost or retracted position, and the piston rod for the cylinder A is in the outermost or advanced position.

The master control valves 65, 70 and 75 are of conventional construction and may be procured at most 10 industrial and commercial valve supply houses. The particular master control valves used in this construction are those known as "Logan #6245 master control valve" as shown in Catalog Bulletin #371, copyrighted 1939 by the Logansport Machine Company, 40 Payson 15 Road, Logansport, Indiana. The bleeder valves Q, P, M, N and O are also of conventional construction, and are known as "Logan #6270 bleeder valve," procurable also from the same company.

As shown in Fig. 1, the construction of the swing cams 20 G, H and K, comprises a cam arm 90, pin mounted on a coupling element 92 threadedly affixed to the piston rod end 94 of the cylinders A, B and E. The cam arm 90 in each instance is arranged on the coupling 92 in such a manner that it will glide over the bleeder valve 25 M, O, or P as the piston rod moves forward, and will engage and release the bleeder valve as the piston rod retracts.

On the ends of piston rods 96 of cylinders C and D, the coupling elements 98 are arranged with a lug 100 30 which is adapted to engage and release the bleeder valves Q and N as the piston rod moves forward.

The first cycle of operation is started by depressing the right foot pedal to activate the built in bleeder valve, shifting the piston of the master control valve 65 from 35 one end to the other and causing the piston in cylinder A to move downward.

As the piston in cylinder A approaches the end of its downward stroke, the swing cam G activates bleeder valve M, shifting the piston of the master control valve 40 70 from one end to the other and causing the pistons in cylinders B and D which operate the side pressure plates 16, to move inwardly. As the pistons in cylinders B and D move inward, the swing cam H passes over the bleeder valve O and does not activate it.

At the end of the inward stroke of the pistons in cylinders B and D, the cam J activates bleeder valve N, shifting the piston of the master control valve 70 to its 45 original position and causing the pistons in cylinders B and D to return to their original positions.

As the pistons in cylinders B and D return to their 50 original positions, the swing cam H activates bleeder valve O, shifting the piston of the master control valve 75 from one end to the other and causing the pistons in cylinders C and E, which respectively operate the toe and heel pressure plates or slides 17 and 18, to move inward. 55 As the pistons in cylinders C and E move inward, the swing cam K passes over the bleeder valve P and does not activate it.

At the end of the inward stroke of the pistons in cylinders C and E, the cam I activates the bleeder valve Q, 60 shifting the piston of the master control valve 75 to its original position and causing the pistons in cylinders C and E to return to their original positions.

As the pistons in cylinders C and E return to their 65 original positions, the swing cam K activates bleeder valve P, shifting the piston of the master control valve 65 to its original position and causing the pistons in cylinder A to return to its original position, thus raising the last structure to the position illustrated in Fig. 1.

The second cycle of the operation is started by depressing the left foot pedal 61. As the foot pedal is depressed, the built-in bleeder valve of the foot pedal is activated, shifting the piston of the master control valve 80 from one end to the other and causing the piston in cylinder F, which actuates the press member 50 to move downward. 70 After the completion of the downward stroke of the piston

in cylinder F, the foot pedal is released and the built-in bleeder valve of the foot pedal is activated, shifting the master control valve 80 to its original position and causing the piston in cylinder F to return to its original position. The second cycle of operation is thus completed.

It will be noted that both sides of the bleeder valve for the left foot pedal 61 are used for actuation of the master control valve 80, whereas one side of all the other bleeder valves is plugged as shown in Fig. 20, since two separate bleeder valves are utilized for actuation of each of the master control valves 65, 70 and 75.

Referring to Fig. 20, the bleeder valve comprises a housing structure 100 having a central bore 101 in which a guide member 102 is secured. A plunger assembly 103 comprising an operating button 104, a shaft 105, and a piston 106 is mounted in the bore. A spring 107 tends to separate the piston 106 from the guide member 102, but this force is normally overcome by a larger spring 108 separating the operating button 104 from the guide member 102. Two control valve ports, 109 and 110, and a bleed port 111, are provided in the housing structure 100. Ports 109 and 110 communicate with the central bore 101 respectively through passages 109a and 110a. The bleed port 111 is open directly into the central bore 101. In the normal position shown in Fig. 20, the bleed port 111 is thus communicating with port 109. All the bleeder valves except the one for foot pedal 61 have a plug 113, so that the normal position of the valves will be closed. The valve associated with foot pedal 61 does not have the plug, the port 109 being suitably connected with the control valve 80 as shown in Fig. 7. When the operating button 104 is actuated, either by a foot pedal or a cam, the shaft 105 moves downward. The piston 106 is forced downward by the spring 107 and blocks off the passage 109a. The shaft 105 then continues moving to open up a central port 106a through the piston 106. Thus the bleed port 111 will be in communication with the port 110, which is connected to the control valve.

Referring to Fig. 19, the control valve comprises a housing structure 125 having a central chamber 125a in which a piston guide member 126 is secured. A spool piston assembly 127 is slidably mounted in the chamber 125a. An air pressure inlet 128, passage 128a, two pressure outlet ports 129 and 130, and two bleed ports 131 and 132 are provided in the housing structure 125 as illustrated. The bleed ports 131 and 132 of control valve 80 are respectively connected to bleeder valve ports 109 and 110 of the bleeder valve operated by the foot pedal 61. The bleed ports 131 and 132 of the other control valves are connected to the port 110 of their respective bleeder valves.

In operation, pressure entering the port 128 will be ported through passages 128a to actuate the spool piston assembly 127 toward either port 131 or 132, depending on the actuation of the bleeder valve opening a passage for air escape through the port 111 and causing a differential between the ends of the piston 127. Air pressure passes through a passage 133 in the guide member 126 to an inner annular passage 134 around the spool piston 127 and then through a passage 135 or 136 to the respective port 129 or 130, depending on the position of the piston assembly 127. Air pressure is thus directed to the appropriate port of the actuating cylinders shown in Fig. 7.

While I have described in detail but one preferred form of construction, it will be apparent to those skilled in the art to which my invention pertains that various changes and modifications may be made therein without departing from the spirit of the invention or from the scope of the appended claims.

I claim:

1. In a machine for the manufacture of doll shoes and the like, a shoe last for supporting a shoe upper in such a position that the edges of said shoe upper project above the top peripheral edge of said shoe last and for supporting a shoe sole on the top face thereof bounded by said projecting shoe upper portion, and means for folding

over and securing said projecting shoe upper portion onto said shoe sole comprising a side pair of sliding pressure plates operable to advance toward said shoe last and partially overlay the shoe last at the innermost limit of their travel and subsequently retracted after having folded over and secured said projecting shoe upper portion to the shoe sole, and a second pair of sliding pressure plates operable to advance toward the toe and heel portions of said shoe last after said side pair of plates has been retracted and to partially overlay the toe and heel portions of the shoe last at the innermost limit of their travel to secure the toe and heel portions respectively of said shoe upper to the toe and heel portions of said sole, said innermost travel of said second pair of sliding pressure plates respectively extending to partially overlap the previous innermost travel of said side pair of sliding pressure plates, the inner edges of said second pair of pressure plates being concave in plan and constructed to first engage the shoe upper at the side of the shoe and to progressively fold over and secure successive upper portions extending towards the center of the toe and heel portions thereof.

2. In a machine for the manufacture of doll shoes and the like, a shoe last for supporting a shoe upper in such a position that the edges of said shoe upper project above the top peripheral edge of said shoe last and for supporting a shoe sole on the top face thereof bounded by said projecting shoe upper portion, and means for folding over and securing said projecting shoe upper portion onto said shoe sole comprising a side pair of sliding pressure plates operable to advance toward said shoe last and partially overlay the shoe last at the innermost limit of their travel and subsequently retracted after having folded over and secured said projecting shoe upper portion to the shoe sole, and a second pair of sliding pressure plates operable to advance toward the toe and heel portions of said shoe last after said side pair of plates has been retracted and to partially overlay the toe and heel portions of the shoe last at the innermost limit of their travel to secure the toe and heel portions respectively of said shoe upper to the toe and heel portions of said sole, said innermost travel of said second pair of sliding pressure plates respectively extending to partially overlap the previous innermost travel of said side pair of sliding pressure plates, the inner edges of said side pair of pressure plates having projecting tips at each inside corner and beveled on the under side at said inside corners, and the inner edges of said second pair of pressure plates being concave in plan and constructed to first engage the shoe upper at the side of the shoe and to progressively fold over and secure successive upper portions extending towards the center of the toe and heel portions thereof.

3. In a machine for the manufacture of doll shoes and the like, a shoe last for supporting a shoe upper in such a position that the edges of said shoe upper project above the top peripheral edge of said shoe last and for supporting a shoe sole on the top face thereof bounded by said projecting shoe upper portion, and means for folding over and securing said projecting shoe upper portion onto said shoe sole comprising a side pair of sliding pressure plates operable to advance toward said shoe last and partially overlay the shoe last at the innermost limit of their travel and subsequently retracted after having folded over and secured said projecting shoe upper portion to the shoe sole, and a second pair of sliding pressure plates operable to advance toward the toe and heel portions of said shoe last after said side pair of plates has been retracted and to partially overlay the toe and heel portions of the shoe last at the innermost limit of their travel to secure the toe and heel portions respectively of said shoe upper to the toe and heel portions of said sole, said innermost travel of said second pair of sliding pressure plates respectively extending to partially overlap the previous innermost travel of said side pair of sliding pressure plates, the second pair of pressure plates having a concave curved

inner edge in plan and of a curvature to first engage the shoe upper at the side of the shoe and to subsequently fold over and smoothly secure said projecting vamp portions onto the shoe sole with an inward and progressive peripheral action and to finally fold over and secure the upper portion at the center of the toe and heel portions thereof.

4. In a machine for the manufacture of doll shoes and the like, a shoe last for supporting a shoe upper in such a position that the edges of said shoe upper project above the top peripheral edge of said shoe last and for supporting a shoe sole on the top face thereof bounded by said projecting shoe upper portion, and means for folding over and securing said projecting shoe upper portion onto said shoe sole comprising a side pair of sliding pressure plates operable to advance toward said shoe last and partially overlay the shoe last at the innermost limit of their travel and subsequently retracted after having folded over and secured said projecting shoe upper portion to the shoe sole, and a second pair of sliding pressure plates operable to advance toward the toe and heel portions of said shoe last after said side pair of plates has been retracted and to partially overlay the toe and heel portions of the shoe last at the inner most limit of their travel to secure the toe and heel portions respectively of said shoe upper to the toe and heel portions of said sole, said innermost travel of said second pair of sliding pressure plates respectively extending to partially overlap the previous innermost travel of said side pair of sliding pressure plates, the inner edges of said second pair of pressure plates being concave in plan and constructed to first engage the shoe upper at the side of the shoe and to progressively fold over and secure successive upper portions extending towards the center of the toe and heel portions thereof, all said pressure plates being operable in the same horizontal plane.

5. In a machine for the manufacture of doll shoes and the like, a shoe last for supporting a shoe upper in such a position that the edges of said shoe upper project above the top peripheral edge of said shoe last and for supporting a shoe sole on the top face thereof bounded by said projecting shoe upper portion, and means for folding over and securing said projecting shoe upper portion onto said shoe sole comprising a side pair of sliding pressure plates operable to advance toward said shoe last and partially overlay the shoe last at the innermost limit of their travel and subsequently retracted after having folded over and secured said projecting shoe upper portion to the shoe sole, and a second pair of sliding pressure plates operable to advance toward the toe and heel portions of said shoe last after said side pair of plates has been retracted and to partially overlay the toe and heel portions of the shoe last at the innermost limit of their travel to secure the toe and heel portions respectively of said shoe upper to the toe and heel portions of said sole, said innermost travel of said second pair of sliding pressure plates respectively extending to partially overlap the previous innermost travel of said side pair of sliding pressure plates, the inner edges of said second pair of pressure plates being concave in plan and constructed to first engage the shoe upper at the side of the shoe and to progressively fold over and secure successive upper portions extending toward the center of the toe and heel portions thereof, all said pressure plates being operable in the same horizontal plane, means supporting said shoe last above the plane of the pressure plates between cycles of the machine operation to permit assembly of the shoe upper and sole on said last, and means operable to lower the shoe last into an operative position to substantially align the top face of said shoe last on which said sole is mounted with the plane of the under sides of said pressure plates.

6. In a machine for the manufacture of doll shoes and the like, a shoe last for mounting a shoe vamp and an inner sole to which said vamp is to be secured, said last

comprising an extended undercut toe portion and an endwise adjustable heel portion, a clamping means operable to clamp the vamp to said extended toe portion, and means connected with the aforesaid adjustable heel portion urging and holding said clamp out of clamping position on adjustment of the heel portion inwardly of the last and releasing said clamp into clamping position on adjustment of the heel portion outwardly of the last.

7. In a machine for the manufacture of doll shoes and the like, a shoe last for mounting a shoe vamp and an inner sole to which said vamp is to be secured, said last comprising an extended undercut toe portion and an endwise adjustable heel portion, a clamping means operable to clamp the vamp to said extended toe portion, and means connected with the aforesaid adjustable heel portion urging and holding said clamp out of clamping position on adjustment of the heel portion inwardly of the last and releasing said clamp into clamping position on adjustment of the heel portion outwardly of the last, said adjustable heel portion comprising an eccentric cam structure rotatably mounted on said last.

8. In a machine for the manufacture of doll shoes and the like, a shoe last for mounting a shoe vamp and an inner sole to which said vamp is to be secured, said last comprising an extended undercut toe portion and an endwise adjustable heel portion, a clamping means operable to clamp the vamp to said extended toe portion, and means connected with the aforesaid adjustable heel portion urging and holding said clamp out of clamping position on adjustment of the heel portion inwardly of the last and releasing said clamp into clamping position on adjustment of the heel portion outwardly of the last, said adjustable heel portion comprising an eccentric cam structure having a stub shaft rotatably mounted vertically in said shoe last, an arm secured to said shaft, a slot in said last through which said arm projects, said arm being movable manually to rotate the eccentric cam structure, said slot limiting the movement of said arm and so constructed and arranged to permit outward adjustment of said heel portion and the application of said toe clamp when the arm is at one end of the aforesaid slot and when said arm is moved to the other end of the aforesaid slot to adjust the heel portion inwardly and to release the clamp to thereby release the vamp from said shoe last.

9. In a machine for the manufacture of doll shoes and the like, a shoe last for mounting a shoe upper and an inner sole to which said upper is to be secured, said last comprising an extended undercut toe portion and an endwise adjustable heel portion comprising a rotatable cam, a clamping means operable to clamp the upper to said extended toe portion, means connected with the aforesaid adjustable heel portion urging and holding said clamp out of clamping position on adjustment of the heel portion inwardly of the last and further operable to release said clamp into clamping position on adjustment of the heel portion outwardly of the last, said means comprising a second cam operable simultaneously with said first cam and an intermediate actuator supported by said last and connecting said second cam with the clamping means, whereby to positively retract said clamp to a release position on adjustment of said first cam effecting an adjustment of said heel portion inwardly of the last to release the upper from said last.

10. In a machine for the manufacture of doll shoes and the like, a shoe last for mounting a shoe upper and an inner sole to which said upper is to be secured, said last comprising an extended undercut toe portion and an endwise adjustable heel portion comprising a first rotatable cam, a clamping means operable to clamp the upper to said extended toe portion, means connected with the aforesaid adjustable heel portion urging and holding said clamp out of clamping position on adjustment of the heel portion inwardly of the last and further operable to release said clamp into clamping position on adjustment of the heel portion outwardly of the last, said means comprising a second cam operable simultaneously

with said first cam, and an intermediate actuator supported by said last and connecting said second cam with the clamping means, whereby to positively retract said clamp to a release position on adjustment of said first cam effecting an adjustment of said heel portion inwardly of the last to release the upper from said last, said clamp comprising a bell crank rotatably supported by said last, one arm of said bell crank clamp being engaged by said actuator and said other arm of said bell crank clamp engaging the toe portion of said last, and spring means urging said last mentioned arm of said bell crank clamp into clamping engagement with the toe portion of said last.
